CLAIM

The ornamental design for a sensor receptacle, as shown and described.

DESCRIPTION

FIG. 1 is an upper perspective view of a sensor receptacle. FIG. 2 is a top view of the sensor receptacle as shown in FIG. 1; and,

FIG. 3 is a bottom view of the sensor receptacle as shown in FIG. 1.

The front, rear, left and right side of the sensor receptacle form no part of the design.

The broken lines in the drawings represent a sensor receptacle and form no part of the claimed design.
